Inventor.

Sam. Utter

Received Letter of New York No. 9.
Letters Patent No. 3467. Dated Sept. 25. 1866.

DES. 2467

Letters Patent No. 3467. Dated Sept. 25. 1866.

Design for a Stove Ornament.

The Schedule referred to in the preceding Patent and making part of this same.

In application it may concurre.

Be it known that I, Samuel, Ritter of the City, County and State of New York, do invent a new and Improved Design for Stove Ornament, and I do hereby declare that the following is a full, clear, and exact description thereof which will enable others skilled in this art to make and use the same, reference being had to the accompanying drawing forming part of this Specification.

The drawing represents a facsimile of this invention.

This Design relates to a Stove Ornament composed of an elliptical, or oval plate, ornamented by a series of rays, which radiate from a common centre, and which extend to different distances from said centre or beyond the circumference of the plate. On the face of the plate and over the radiating rays are the letters N. S. W., standing for "National Stove Works", and these letters are interlaced so that they form a unique and ornamental group. Round the letters N. S. W. and equidistant from the circumference of the plate is a chain composed of a series of circular links, the whole being arranged, so as to produce a new and ornamental design.

A represents a plate which is oval or elliptical and from the centre of which radiate the rays a, as shown. On the face of said plate are the letters N. S. W. and these letters are surrounded by the chain b.

That I claim as new and desire to secure by Letters Patent, is,

The Design for a Stove Ornament as herein shown and described.

W. Ritter.
